UNITED STATES PATENT OFFICE.

PERCY WADE, OF WASHINGTON, DISTRICT OF COLUMBIA.

ACETYLENE GENERATOR.

Application filed September 23, 1920. Serial No. 412,198.

To all whom it may concern:

Be it known that I, PERCY WADE, a citizen of the United States, residing at Washington, District of Columbia, have invented 5 certain new and useful Improvements in Acetylene Generators; and I do hereby declare the following to be a full, clear, and exact description of the invention, such as will enable others skilled in the art to which 10 it appertains to make and use the same.

This invention relates to apparatus adapted for use in the generation of acetylene gas by the reaction of calcium carbide and water.

15 The invention is designed primarily to supply acetylene from a carbide generator under a predetermined and automatically controlled pressure, sufficient, for example, for use in acetylene torches of the pressure type.

It is an object of the invention to produce an apparatus of the type described in which the gas may be generated under adequate pressure in one unit, or set of units, washed 20 in another unit, stored under pressure in a third unit, the latter of which may, for purposes of safety, be sunk beneath the ground, and to regulate the generation of gas in accordance with the pressure in the receiving tank.

A further object is to build an apparatus of the class described in units that may be conveniently distributed in accordance with the available space.

35 Other objects of the invention are to regulate the generation of gas in response to the pressure of the generated gas; to provide a generator unit wherein the cooling water is in direct contact with the outside of the carbide holder and wherein the carbide holder is without holes or notches to admit the water to the carbide, the water flowing successively over the sides of the holder to the several pockets in succession; to provide a 40 simple safety appliance so that excess of pressure within the generator may be released before the danger point is reached.

With these and other objects in view the invention consists in the combination and in 45 the subcombinations set forth in the ensuing

description, illustrated in the drawings and defined in the appended claim.

In the drawings:

Figure 1 illustrates diagrammatically the several parts of the apparatus and their relationship to each other;

Figure 2 is a longitudinal section through the carbide holder and gas generator;

Figure 3 is a section on line 3—3 of Figure 2;

Figure 4 is a perspective of the lower end of the generator tank;

Figure 5 is a perspective of one end of the carbide holder;

Figure 6 is a perspective of a cover for the generator tank.

Similar reference characters designate similar parts throughout the several views.

In the drawings, 1 designates the casing of the generator or what may be designated as the generator tank. The said tank is preferably made of sheet metal provided with welded joints; it consists of a rectangular elongated casing permanently closed at one end 2 and opened at the end 3. Said tank is preferably bound with a plurality of spaced metal bars 4 embracing it transversely for strengthening purposes.

Overhanging the upper side at end 3 of tank 1 and welded or otherwise secured thereto is a fastening member 5 provided with a hook affording an opening 6 adapted to admit, laterally, a spring locking bar, presently to be described. To the lower side of the tank or casing 1, directly opposite the fastening member 5, a fastening member 7 overhangs the end, said member having a hole 8. The member 7 is also welded or otherwise firmly secured to the casing.

A cover 9 corresponding in shape to the end of the tank or casing is adapted to close the open end thereof, suitable gaskets being provided whereby the said cover may fit fluid tight. At top and bottom of the said cover 9 are slotted ears 10 through which the members 5 and 7 are adapted to pass when the cover is affixed to the end of the casing. In order to secure the cover in place a spring locking bar 12 is provided, said bar having an outward bowed central

portion, an end 13 adapted to be inserted in the orifice 8 of the member 7, and an end 14 adapted to be passed sideways into the opening 6 of the hook member 5. Threaded through a hole in the center of the bowed portion of the locking bar 12 is a screw 15, the inner end of which is adapted to engage with a shallow socket 11 in the center of the cover 9.

10 By placing the cover 9 against the end of the casing 1, as described, inserting the spring locking bar 12 in the openings in said members 5 and 7, and turning the screw 15 so as to press the cover 9 against the end of the tank or casing 1, a secure fastening is obtained, but one which will yield under excessive pressure, the spring locking bar tending to buckle outward and release the cover 9 so that gas under pressure and water may escape between it and the edge of the tank or casing. It will be apparent that the pressure under which it may be desired that the bar 12 may yield may be precalculated so that the said bar 25 may be made and clamped so as to yield to any desired pressure.

15 The carbid holder 20 comprises a rectangular tank open at the top and divided into a number of pockets or compartments 30 by cross partitions 21. The carbid holding tank is made sufficiently smaller in cross section than the casing 1 so that when the holder is pushed into the tank or casing 1 through the open end 3 there will be a restricted water space on each side of the holder. At one end of the said carbid holder 20 holes 22 are provided for the purpose of engaging a hook by means of which the holder may be removed from 40 the casing for purposes of emptying the waste lime and recharging the holder with fresh carbid.

20 In use, the casing 1 will be supported at an incline to the horizontal by any suitable support such as S, the end 2 being arranged higher than the end 3. At one side of the casing adjacent to the higher end 2 is an inlet 30 into which is tapped a water pipe 50. The water inlet discharges 50 into the space between the carbid holder 20 and the wall of the tank or casing 1. An outlet 21 for gas is provided through the top of the casing 1 near the end 2. A check valve 32 is contained within a casing 55 32 communicating with the outlet 31, said check valve opening under the pressure of gas escaping from the casing and seating under pressure in the opposite direction.

60 A pipe 33 leads from the gas outlet 31 to a gas washer 34 and a check valve 35 is preferably provided adjacent the inlet to the washer 34, said valve opening under the pressure of gas seeking to enter the washer

and closing in response to pressure in the opposite direction. The washer 34 consists of a closed tank containing water or other suitable washing fluid or other material; a pipe 36 is in communication with pipe 33 and extends nearly to the bottom of the tank so that gas entering will go to the bottom of the water or other washing fluid and then rise therethrough.

65 From the top of the washer 34 extends a gas pipe 37 which leads to a pressure tank 38 in which the gas is stored under suitable pressure for use in a shop or elsewhere. From the tank 38 a suitable gas offtake 39 is provided for supplying gas to torches 70 or other burners.

75 In order to maintain pressure in the tank 38 I provide a water tank 40 which may be placed in an upper story at a height sufficient to provide the required pressure. A pipe 41 connects the bottom of tank 40 with the bottom of tank 38.

80 In the embodiment illustrated the water pipe 50 connected to the inlet valve 30 of the generator communicates with a city water main, as by means of a pipe 51, in which is a check valve 52 designed to open in order to admit water through the pipe 50 into the tank 1. Said valve 52 is, however, controlled by any suitable pressure responsive device 53, herein shown as of the expansible chamber type, arranged to be responsive to pressure in the tank 38, the chamber of said pressure responsive device being in communication, by means of a small pipe 54, with said tank 38. By 85 this arrangement it will be apparent that the pressure responsive device 53 will close the valve 52 and prevent the passage of water whenever pressure in the tank 38 has reached a certain predetermined pressure for which the said regulator is set and will open when the pressure is less than the predetermined amount; and it will be apparent that if it is desired to maintain any predetermined amount of pressure in the tank 38, said pressure responsive device will be so adjusted that when the pressure exceeds that amount the device 53 will close the valve 52 and cut off the water supply whereupon the generator will cease 90 operating because of the lack of water.

95 From the construction described it will be seen that water flowing into the casing 1 will gradually fill the lower end thereof up to the top edge of the lowest carbid pocket and will flow over into the said lowest pocket. The generation of gas will then begin and will continue until the carbid in the lowest pocket is exhausted. If no more 100 gas is needed at this time the water supply can be cut off. If a continuous supply of gas is needed the flow of water continues 105 and next enters over the sides of the pocket 110

next to the lower pocket whereupon gas begins to generate from the carbid in the next lowest pocket, and so the carbid in each pocket from lowest to highest reacts in succession with the water pouring over the sides, and should it be desired to stop the production of gas at any time it is simply necessary to cut off the water supply. The plant is self regulating with respect to the quantity of gas supply, by means of the pressure responsive device 53 which controls the admission of water, said device responding directly to the pressure of the gas in the equalizing or storing tank 38, as described.

By reason of the readily portable separate units of which the outfit is constructed, this plant may be distributed in shops where there is limited room because the several units may be disposed in places that would otherwise be waste room. The washer and gas tank may be disposed out of doors, and the latter be buried in the earth, if desired.

The safety appliance disclosed is extremely simple, requires no expensive valves and is thoroughly efficient; there being no holes or notches to become plugged up with lime during the reaction in the generation of gas, the generator cannot become choked and cease operating as sometimes happens with generators of this type in which water is admitted to the several pockets through holes or notches. The tank or tanks 1 may be so disposed that the end into which the carbid holder is inserted and through which it is removed may be out of doors, the tank

extending through the wall of the shop or other building. Thus no wet lime or residue need be scattered over the floor.

The thin layer of water in contact with the side walls of those carbid cells which contain carbid and water in violent reaction, will tend to cool the walls of the holder, and will transmit the heat to the tank 1 which is exposed to the outer air.

By means of the control of the water supply in response to pressure of the generated gas, only so much gas will be generated as the torches or burners demand, and the evolution of gas will cease automatically when there is a sufficient supply in the pressure tank.

Having described my invention in such manner as to enable those skilled in the art to make and use the same what I claim and desire to secure by Letters Patent is:

In a gas generating apparatus of the class described comprising an elongated inclined gas-tight casing, a plural compartment carbide holder of lesser size than and adapted to be positioned within the said casing, means for admitting water at the upper end of said casing between the casing and container so that the water may run down between said casing and container to cool said container and to fill the lowermost compartment and then overflow into the several compartments of the container one after the other as the height of the water increases.

In testimony whereof I affix my signature.

PERCY WADE.
